(57) **CLAIM**

The ornamental design for a fluid container, as shown and described.

DESCRIPTION

The patent or application file contains at least one drawing executed in color. Copies of this patent or patent application publication with color drawing(s) will be provided by the Office upon request and payment of the necessary fee.

FIG. 1 shows a front elevation view of novel fluid container of the present invention having a translucent core portion surrounded by opaque shell portion;

FIG. 2 depicts a back elevation view of the novel fluid container of FIG. 1;

FIG. 3 shows a left side elevation view of the novel fluid container of FIG. 1, revealing the contours of the neck portion of the translucent core portion of the novel fluid container; FIG. 4 shows a right side elevation view of the novel fluid container of FIG. 1;

FIG. 5 depicts a top plan view of the novel fluid container of FIG. 1, showing an open oval aperture enclosed by the opaque shell, said open oval aperture reveals a solid colored retention cap;

FIG. 6 illustrates a bottom plan view of the novel fluid container of FIG. 1, showing a translucent oval feature enclosed by the opaque shell; and,

FIG. 7 shows a left, front perspective view of the novel fluid container of FIG. 1.

The portion of the design shown in broken lines in FIGS. 1 and 7 is disclaimed by the Applicant as being part of the invention.
